United States Patent

Des. 237,307
Patented Oct. 21, 1975

237,307

RADIO RECEIVER

Masaaki Miyamoto, Moriguchi, and Hironosuke Koda,
Kyoto, Japan, assignors to Matsushita Electric Industrial Co.

Filed Nov. 8, 1973, Ser. No. 414,104

Claims priority, application Japan May 11, 1973

Term of patent 14 years

Int. Cl. D14—03

U.S. Cl. D56—4 B

FIG. 1

FIG. 2

FIG. 3

FIG. 1 is a front, top and right side perspective view of a radio receiver showing our new design;

FIG. 2 is a front, top and left side perspective view; and

FIG. 3 is a front elevational view.

The rear of the radio receiver is identical to the front except for the omission of the antenna and support pocket therefor.

We claim:

The ornamental design for a radio receiver, as shown and described.
